BLOTTING DEVICE

Robert F. Howe, Leominster, Mass.

Application August 4, 1953, Serial No. 372,320

1 Claim. (Cl. 120—24)

This invention relates to blotting devices and more particularly to blotters of the rocker type.

A principal object of the present invention is to provide a blotter of the rocker type wherein the blotter carries advertising matter, calendars and the like which is continuously in view to the user of the blotter, and which is continuously in view to the observer when resting on the top of a desk, table or other supporting surface.

Another object of the invention is to provide a rocker type blotting device wherein the blotter is readily attached and detached.

A further object of the invention is to provide a blotter of the rocker type with a carrier for the blotter and a blotting sheet which are readily snapped into clamping position.

Still another object of the invention is to provide a blotter of the rocker type with a carrier having means for guiding the blotting sheet to operative position and for holding the blotting sheet firmly against displacement thereon.

It is further proposed to provide a blotter of the rocker type which is simple and durable in construction and which may be manufactured and sold at a reasonable cost.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure;

Figure 1 is a perspective view of a blotter made in accordance with my invention.

Figure 2 is a spread perspective view thereof, the blotter being shown in flat condition.

Figure 3 is an enlarged sectional view taken on the plane of the line 3—3 of Figure 1.

Referring to the drawing in detail, the improved blotting device includes a rocker member comprising a body 5, semi-oval in longitudinal section formed of a thin sheet of transparent resilient plastic material adapted to be bent to shape. A cover in the form of a plate 6 of similar transparent plastic material connects the ends of the body 5. The cover 6 is thick in order to provide a rigid connection and is formed with downwardly extending integral flanges 7 at its ends, the outer surfaces of the flanges being curved to conform to the curvature of the body 5.

A blotter 8 is placed around the exterior of the body 5 of the rocker member and the ends 9 of the blotter are

2

provided with elongated die cuts or slots 10 to receive transverse elongated protuberances 11 formed integrally on the ends of the body 5. The blotter is preferably of the double face type with the blotting paper or surface 12 on one side and with the glazed surface 13 on the other side. A calendar 14 may be printed adjacent one end of the glazed surface, and the remainder of said surface may be reserved for advertising matter or the like such as indicated at 15. The printed glazed surface is placed against the material of the body 5 and can be viewed through the transparent cover 6 and the curved body 5.

In assembling the blotting device, the slotted ends of the blotter 8 are placed over the protuberances 11 on the curved body 5 and then this unit is attached to the cover plate 6 by snapping the protuberances into elongated transverse slots 16 formed in the flanges 7 of the cover plate. The blotter 8 may be readily removed and a fresh blotter substituted by merely squeezing the ends of the curved body 5 and lifting off the cover plate 6.

When the blotting device is in assembled condition, the glazed surface 13 of the blotter with its calendar and advertising matter is in full view of the user of the blotting device, and is in full view of the observer when the device is resting idly on a desk, table or other supporting surface.

It will be noted that no separate fastening elements such as clips, bolts and the like are needed in order to hold the blotting device in assembled condition.

Furthermore, the cover plate 6 serves as a ready handle for manipulating the blotting device during the blotting operations.

While I have illustrated and described the preferred embodiment of my invention, it is to be understood that I do not limit myself to the precise construction herein disclosed and the right is reserved to all changes and modifications coming within the scope of the invention as defined in the appended claim.

I claim:

40 A blotting device comprising a curved resilient transparent plastic body, semi-oval in longitudinal section and having elongated transverse protuberances along its end edges, a blotter positioned around the exterior of the curved body, said blotter having elongated transverse slots along its end edges for receiving and interlocking with the protuberances on said curved body, said blotter having a blotting surface on one side and a glazed surface on the other side, and a flat rectangular-shaped transparent plastic cover plate having end flanges with transverse slots therein for detachably receiving and interlocking with the protuberances of the body and for clamping the blotter between the body and plate, said blotter having indicia on its glazed surface visible through the cover plate.
